(57) **CLAIM**

The ornamental design for a motorcycle license plate, as shown and described.

DESCRIPTION

FIG. 1 is a right side view of a motorcycle license plate showing our design in an intermediate position;

FIG. 2 is a left side view thereof;

FIG. 3 is a top side view thereof;

FIG. 4 is a bottom side view thereof;

FIG. 5 is a rear view thereof;

FIG. 6 is a front view thereof;

FIG. 7 is a perspective view thereof;

FIG. 8 is a perspective view of the motorcycle license plate showing our design in a deployed position; and,

FIG. 9 is a perspective view of the motorcycle license plate showing our design in a retracted position.

It will be understood that the dashed lines presented in the drawings are for illustrations only, and do not form a part of the claimed design.
